Primary Examiner — William L Miller*(74) Attorney, Agent, or Firm* — Lawrence J. Gibney; Mitchell Ghaneie**ABSTRACT**

The present invention is a device that assists with securing packages of varying sizes to the door or a home, apartment, or business. The device is capable of collapsing when not in use or while hanging on the user's door. Once a package is delivered and dropped into the secured apparatus, only the user will have access to the package by unlocking a pick-up door located on the device's bottom enclosure and retrieving the package from an interior bag. The user may additionally provide an enlarged bag to hang and secure to the outside of the device, if the package is expected to be too large to fit within the bottom enclosure of the apparatus.

PARCEL SECURITY APPARATUS

BACKGROUND OF THE INVENTION

A. Field of the Invention

The present invention relates to securing a delivered package at the door of a residence or commercial building if that occupant is not present.

B. Prior Art

While there are many parcel security devices utilized today, none provide the unique and novel features provided by the present invention. Current parcel security devices are incapable of attaching to the exterior of a door, accommodating a variety of differently sized parcels, or both. A representative example of the prior art can be found in the following patents.

In U.S. Pat. No. 5,624,071 an apparatus for receiving packages is disclosed. While this invention hangs from the top of a door, it is not capable of accepting larger packages, such as shoe boxes or boxes containing electronics. The '071 patent also does not collapse or contain an interior bag.

In U.S. Pat. No. 4,909,052 a door safe for delivery and pickup of articles is disclosed. The door safe is hung from the top of the door and is capable of securing relatively small items.

In U.S. Pat. No. 9,364,112 a secure portable apparatus for accepting parcels and deliveries is disclosed. This invention is attached to the doorknob or door handle of a door and rests on the ground. Furthermore, this device does not collapse or provide an interior bag similarly to the two references above.

BRIEF SUMMARY OF THE INVENTION

The present invention is a parcel security apparatus that is capable of hanging from the top of a door, securing packages, and collapsing. Having packages delivered to one's home or business is becoming an increasingly more popular way to shop. However, the home or business owner is often not sure when her or his package is to be delivered or cannot be home when the package is delivered. Accordingly, package theft is a significant concern of home or business owners, which can be mitigated with the use of the present invention.

This invention will allow individuals to secure a package while she or he is away by providing a secure drop off door and a secure accessible enclosure, which is located directly beneath the drop off door. Once a package is submitted through the drop off door it falls into an interior bag within the bottom enclosure for pick up later. The bottom enclosure provides a lockable pick-up door and is collapsible.

Beneath the bottom enclosure is a plurality of hooks that can hold a larger bag for securing big packages such as televisions, speakers, computers, as well as small furniture boxes and other large products.

The device may also provide alarm and notification features that inform neighbors or the user's mobile communication device that a package has been delivered or that the device is being tampered with.

BRIEF DESCRIPTION OF THE DRAWINGS

FIG. 1 is front view of the device, which is showing the top enclosure and the bottom enclosure.

FIG. 2 is a bottom view of the device.

FIG. 3 is a top view of the device.

2

FIG. 4 is a side view of the device, which is depicting the drop off door, interior bag in dotted lines, interior locking brace in dotted lines, and track in dotted lines.

FIG. 5 is a side view of the device, which is showing the bottom enclosure in a collapsed position.

FIG. 6 is a front view of the device, which is showing the pickup door in an opened position and therefore showing the interior bag.

FIG. 7 is an in-use front view of the device which is holding an exterior bag from the bottom of the device.

FIG. 8 is a diagram of the device and the components that is comprised of.

DETAILED DESCRIPTION OF THE EMBODIMENTS

This invention is a collapsible parcel security apparatus which is comprised of a top enclosure 6, a bottom enclosure 8, a hanger 15, and an interior bag 30. The top enclosure 6 is comprised of a drop off door 10, drop off door handle 11, a drop off door hinge 12, and a track 35. The bottom enclosure 8 is further comprised of a pick-up door 20, at least one pick-up door handle 21, at least one pick-up door hinge 22, a lock 23, a plurality of pins 24, at least one hook 25, a plurality of hinges 40, and at least one brace 45. The interior bag 30 is flexible in nature and provides a zipper as depicted in FIG. 6. The hanger 15 is located at the top of the device.

The drop off door 10 is a security door that prevents an individual from reaching inside the device. The drop off door 10 has a handle 11 and rotates along a hinge 12. A track 35 is provided at the bottom of the top enclosure 6, which is shown in FIG. 4. The interior bag 30 has an open end and a closed end. The open end of the interior bag is attached to the interior of the top enclosure 6 above the track 35 and the closed end hangs into the bottom enclosure 8, which is also shown in FIG. 4.

With attaching the interior bag 30 above the track 35, the apparatus may remain secured even when the bottom enclosure 8 is in a collapsed position. Accordingly, when the bottom enclosure 8 is collapsed the interior bag is exposed. Thus, it is anticipated that the bag can be knife resistant or

cut resistant. It is further anticipated that a knife resistant shield may be provided over a portion of the bag that is left exposed when the bottom enclosure **8** is collapsed.

The bottom enclosure **8** has a first side, a second side, a top end, a bottom side, a front side, and a back side. The first side, second side, and bottom side, each provide two panels respectively, which is shown in FIG. 2, FIG. 3, and FIG. 4. The two panels on each respective side are connected to each other with a hinge **40**. One of the two panels of the first side, second side, and bottom side is attached to the back side of the bottom enclosure **8** with a hinge **40**. The other panel of each the first side, second side, and bottom side is attached to the front side of the bottom enclosure **8** with a hinge **40**.

A locking brace **45** is provided between the two panels of the first and second sides of the bottom enclosure **8**. FIG. 4 shows the locking brace **45** in dotted lines on a side of the bottom enclosure **8**.

The pick-up door **20** has a pick-up door handle **21**, a lock **23**, and a pick-up door hinge **22**, which is shown in FIG. 1. The pick-up door hinge **22** is provided on the front side of the bottom enclosure **8** and allows the pick-up door **20** to rotate between an open and closed position. The pick-up door handle **21** allows a user to open and close the pick-up door **20** as well as collapse and expand the bottom enclosure **8**.

The bottom enclosure **8** additionally provides a plurality of pins **24**. The pins **24** fit within a set of parallel tracks **35** and slide along the track **35** when the bottom enclosure **8** is pulled or pushed between collapsed and expanded positions. When the bottom enclosure **8** is fully expanded, the interior locking braces **45** will lock the bottom enclosure **8** in the expanded position. The user must open the pick-up door **20** and unlock each locking brace **45** from inside the bottom enclosure **8** to then bring the bottom enclosure to a collapsed position. While it is not shown in the drawings, it is anticipated that a ratcheting mechanism, push pin, or the like could be utilized to lock the locking braces **45**.

When an individual delivers the package she or he pulls on the drop off door handle **11**, thereby forcing the door **10** to rotate about the drop off door hinge **12**. The individual can then place a package into the door **10** and close the door **10**, thereby allowing the package to then drop into the interior bag **30**.

If the bottom enclosure **8** was initially in a closed position, the delivered package could force the bottom enclosure **8** to expand to an expanded position as the package falls into the interior bag **30**. Alternatively, the delivery person could pull the pick-up handle **21** to then expand the bottom enclosure **8** prior to placing a package into the drop- off door **10**.

Once a package is delivered it is secured until the recipient removes the apparatus from the secured delivery apparatus. The recipient must first unlock the lock **23**, open the pick-up door **20**, open the interior bag **30**, and remove the package accordingly. It is anticipated that the lock **23** could be a lock and key, a combination lock, Bluetooth activated lock, or a biometric fingerprint reader, or the like. It is further anticipated that the interior bag **30** could have an additional locking mechanism.

Some additional features of the device are the use of a vibration detection sensor **55**, an alarm, a controller **70** and an emergency mobile notification transmitter **65**. In turn, the owner of the device would be notified if an individual attempted to steal, break, or otherwise tamper with the device. It is also anticipated that a mobile camera **60** could be provided on the device. The camera **60** would allow for capturing photos or a video of a package being delivered or a mischievous individual tampering with the device. If the

vibration detector is triggered, the controller **70** could implement the camera **60** and alarm as well as send an emergency notification with the transmitter **65** to the user's mobile communication device via Wi-Fi. The camera **60** may be placed in the hangar to provide an elevated view of the surroundings of the parcel security apparatus. However, it is anticipated that the camera **60** could be placed on other parts of the invention.

While the embodiments of the invention have been disclosed, certain modifications may be made by those skilled in the art to modify the invention without departing from the spirit of the invention.

The invention claimed is:

1. A parcel security apparatus, which is comprised of:
  - a. a top enclosure;
    - wherein the top enclosure has a drop-off door;
    - wherein the top enclosure has a drop-off door handle;
    - wherein the top enclosure has a track;
  - b. a bottom enclosure;
    - wherein the bottom enclosure has a pick-up door;
    - wherein the pick-up door is attached to the bottom enclosure with at least one pick-up door hinge;
    - wherein the bottom enclosure has a plurality of panels;
    - wherein the bottom enclosure has a plurality of panel hinges for hingedly connecting adjacent panels of the plurality of panels;
    - wherein the bottom enclosure has a lock for the pick-up door;
    - wherein the bottom enclosure has a plurality of pins;
    - wherein the plurality of pins fit within the track;
    - wherein the bottom enclosure has at least one locking brace provided between at least two adjacent panels of the plurality of panels;
    - wherein the bottom enclosure has a plurality of hooks;
    - wherein the plurality of hooks is attached to the bottom side of the bottom enclosure;
  - c. an interior bag;
    - wherein the interior bag is attached to the top enclosure above the track;
    - wherein the interior bag hangs within the bottom enclosure;
  - d. a hanger;
    - wherein the hanger is attached to the top enclosure.
2. The parcel security apparatus described in claim 1 wherein the plurality of pins slide along the track.
3. The parcel security apparatus described in claim 1 wherein a handle is provided on the pick-up door.
4. The parcel security apparatus described in claim 1 wherein the plurality of hinges and plurality of panels enable the bottom enclosure to collapse and expand.
5. The parcel security apparatus described in claim 1 wherein the interior bag is knife resistant.
6. The parcel security apparatus described in claim 1 wherein the interior bag has a zipper.
7. The parcel security apparatus described in claim 1 wherein the hooks can hold an exterior bag.
8. The parcel security apparatus described in claim 7 wherein the exterior bag can accommodate oversized packages.
9. A parcel security apparatus, which is comprised of:
  - a. a top enclosure;
    - wherein the top enclosure has a drop-off door;
    - wherein the top enclosure has a drop-off door handle;
    - wherein the top enclosure has a track;
  - b. a bottom enclosure;
    - wherein the bottom enclosure has a pick-up door;

wherein the pick-up door is attached to the bottom enclosure with at least one pick-up door hinge; wherein the bottom enclosure has a plurality of panels; wherein the bottom enclosure has a plurality of panel hinges for hingedly connecting adjacent panels of the plurality of panels; wherein the bottom enclosure has a lock for the pick-up door; wherein the bottom enclosure has a plurality of pins; wherein the plurality of pins fit within the track; wherein the bottom enclosure has at least one locking brace provided between at least two adjacent panels of the plurality of panels; wherein the bottom enclosure has a plurality of hooks; wherein the plurality of hooks is attached to the bottom side of the bottom enclosure; 15

c. an interior bag; wherein the interior bag is attached to the top enclosure above the track; wherein the interior bag hangs within the bottom enclosure; 20

d. a hanger; wherein the hanger is attached to the top enclosure.

e. a sensor; wherein the sensor is a vibration sensor; wherein the sensitivity of the sensor is programmable; wherein the sensor is attached to the interior of the bottom enclosure; 25

f. a camera; wherein the camera is capable of taking pictures; wherein the camera is capable of taking video; wherein the camera is attached to the hanger;

g. a transmitter; wherein the transmitter transmits pictures to a remote device; wherein the transmitter transmits video to a remote device; wherein the transmitter transmits preprogrammed messages to a remote device; wherein the transmitter is attached to the interior of the bottom enclosure; 10

h. a controller; wherein the controller is programmable; wherein preset features can be programmed into the controller; wherein the controller is attached to the interior of the bottom enclosure.

10. The parcel security apparatus described in claim 9 wherein the pins slide along the track.

11. The parcel security apparatus described in claim 9 wherein a handle is provided on the pick-up door.

12. The parcel security apparatus described in claim 9 wherein the plurality of hinges and plurality of panels enable the bottom enclosure to collapse and expand.

13. The parcel security apparatus described in claim 9 wherein the interior bag is knife resistant.

14. The parcel security apparatus described in claim 9 wherein the interior bag has a zipper.

15. The parcel security apparatus described in claim 9 wherein the hooks can hold an exterior bag.

16. The parcel security apparatus described in claim 15 wherein the exterior bag can accommodate oversized packages.
